(57) **CLAIM**

The ornamental design for a cremation ash capsule, as shown and described.

DESCRIPTION

FIG. 1 is a front perspective view of a cremation ash capsule showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof; and,

FIG. 5 is a bottom plan view thereof.

The broken lines in FIG. 1 showing a photo of a loved one depicts environmental matter that forms no part of the claimed design.
